United States Patent Office

Des. 203,709
Patented Feb. 8, 1966

203,709

WATER CAN

Kim Yamasaki, Chicago, Ill., and Harold V. Tibbets and
James F. Hutchison, Houston, Tex., assignors to Texas
Tennessee Industries, Inc., Houston, Tex., a corporation
of Texas

Filed Mar. 10, 1965, Ser. No. 84,201

Term of patent 14 years

(Cl. D58—17)

Fig. 1

Fig. 2

Fig. 3

FIGURE 1 is a front elevational view of a water can, showing our new design;

FIGURE 2 is a right elevational side view thereof;

FIGURE 3 is a top plan view thereof;

FIGURE 4 is a front elevational view of a modified form of the water can shown in FIGURE 1 wherein the same has been reduced in size and the center band is correspondingly reduced;

FIGURE 5 is a right elevational side view thereof; and

FIGURE 6 is a top plan view thereof.

We claim:

The ornamental design for a water can, substantially as shown and described.
